UNITED STATES PATENT OFFICE.

RICHARD T. CLARKE, OF COLUMBUS, OHIO.

SUSPENDERS AND TROUSERS CONNECTION.

SPECIFICATION forming part of Letters Patent No. 703,386, dated July 1, 1902.

Application filed August 28, 1901. Serial No. 73,523. (No model.)

To all whom it may concern:

Be it known that I, RICHARD T. CLARKE, a citizen of the United States, residing at Columbus, in the county of Franklin and State 5 of Ohio, have invented a certain new and useful Improvement in Suspenders and Trouser Connections, of which the following is a specification.

My invention relates to the improvement 10 of suspenders and trousers connections of that class which are particularly adapted for use where the suspenders are worn beneath the outer shirt; and the objects of my invention are to provide a simple and inexpensive trous- 15 ers connection of this class, to provide an im- proved button-engaging attachment for the suspender-ends, whereby a trousers-button on the inner side of the trousers-band may be readily and effectively engaged with the sus- 20 pender-end, and to produce other improvements, the details of construction of which will be more fully pointed out hereinafter. These objects I accomplish in the manner 25 illustrated in the accompanying drawings, in

Figure 1 is a view in perspective of a portion of a suspender-strap and its ends, showing my button - engaging device connected with said ends; and Fig. 2 is a sectional view 30 through the upper portion of a trousers-band and through one of the suspender-ends and its attachment, illustrating the manner of connecting the same with the button.

Similar numerals refer to similar parts 35 throughout the several views.

In carrying out my invention I employ a clip of metal or other similar substance which is doubled or bent upon itself at about the center of its length, the body or inner mem- 40 ber of this clip being indicated at 1. As shown in the drawings, this clip-body or inner member preferably tapers toward its lower end and has formed in said lower end portion an opening 2. The upper and wider por- 45 tion of the clip-body 1 has formed therein a transverse slot 3, and above this opening the outer member or portion 1^a is bent downward in front of and out of contact with the portion 1. This outer member terminates in an in- 50 wardly-projecting and thence downwardly-bent end tongue 4. The portion 1^a is in the nature of an open frame, the upper enlarged

or mouth portion leading centrally into the lower socket or contracted neck portion 5, the latter preferably tapering toward its lower 55 end and terminating a short distance above the tongue extension 4. In connecting the above-described device with the buttonhole-containing portions 6^a of the suspender-ends 6 the suspender-end passes through the slot 60 3 of the button-engaging clip from front to rear, thence extends downward on the rear side of the body portion 1 of said clip. As indicated in the drawings, the tongue 4, which forms the termination of the portion 1^a of the 65 clip, is inserted through the clip-opening 2, thence through the lower end of the usual buttonhole 6^b of the suspender - end, after which it is bent downward and clamped or pressed against the rear side of the button- 70 hole-containing portion of said suspender- end, as shown more clearly on that suspender- end which is illustrated on the right of Fig. 1.

In order to properly utilize my device for the connection of suspender-ends with trou- 75 sers-band buttons, the buttons, one of which is indicated at 7 in Fig. 2, are secured in a desirable manner on the inner side of the trou- sers-band 8.

In practice the suspenders are designed to 80 be worn over the undershirt and on the under or inner side of the outer shirt, the connection between a suspender-end and a trou- sers-button being formed readily by insert- 85 ing the head of the button in the mouth of the loop-like portion of the clip 1^a, then forc- ing said button downward until its shank is wedged or closely embraced within the neck portion or socket 5 of said member 1^a. It is obvious that in this operation that portion of 90 the outer shirt which in Fig. 2 is indicated at 9 which is adjacent to the button will be like- wise caught within the neck of the clip.

From the construction shown and described 95 it will be seen that a simple and inexpen- sive suspender-end attachment is provided through the medium of which the suspenders and trousers - buttons may be readily con- nected when said suspenders are worn be- 100 neath the outer shirt.

Having now fully described my invention, what I claim, and desire to secure by Letters Patent, is—

In a suspenders and trousers connection,

the combination with a suspender-end having a buttonhole or similar opening therein, of a button-engaging attachment therefor comprising a doubled clip-body, the inner member thereof having an opening in its upper portion adapted to receive a suspender-end and having an opening in its lower portion and the outer member thereof being in the nature of an open frame having an enlarged upper or mouth portion terminating in a ta-

pering socket or neck and an end tongue 4 adapted to be inserted through the lower end opening of the inner member of the clip and through the opening in a suspender-end, substantially as specified.

RICHARD T. CLARKE.

In presence of—

C. C. SHEPHERD,
A. L. PHELPS.
